Specification of Letters Patent.

Patented Feb. 11, 1919.

Application filed April 29, 1915. Serial No. 24,810.

To all whom it may concern:

Be it known that we, LIBANUS M. TODD and CHARLES G. TIEFEL, both of Rochester, in the county of Monroe and State of New York, have invented certain new and useful Improvements in Check-Writers; and we do hereby declare the following to be a full, clear, and exact description of the same, such as will enable any person skilled in the art to which the invention appertains to make and use the same.

Our invention relates to that class of printing machines which is adapted for marking checks, drafts, and other commercial papers with a monetary value in such an indelible manner as to defy the alteration, or "raising", of the instrument to make it appear payable for a larger amount than was originally intended to be conveyed.

The object of the invention is to provide a simple, compact and convenient machine of the nature described, with a wide range of printing characters, so that the value of the instrument, exact to the cent, may be quickly and easily printed by a protective method which stamps the ink clear through the texture of the paper. More particularly, the present invention provides a machine of this type having a simple and effective operating mechanism; an arrangement of the parts affording the maximum structural strength; a conveniently arranged dial and pointer for facilitating the setting of the type wheel, together with other advantageous features which will become more apparent as the description proceeds, reference being had by numerals to the accompanying drawings forming a part of this specification, in which:

Figure 1 is a top plan view of the machine.

Fig. 2 is an elevation from the left side thereof.

Fig. 3 is a sectional elevation from the left side of the machine with the side of the casing removed.

Fig. 4 is a sectional elevation from the front of the machine taken on line 4-4 of Fig. 3.

Fig. 5 is a sectional elevation from the right side, the side of the casing being removed.

Fig. 6 is a top plan view with the top 55 of the casing removed.

Fig. 7 is a detail view from above, of the pointer for the dial with its carriage, and a portion of the guide rail.

Fig. 8 is an elevation of the same from 60 the left side of the machine.

Fig. 9 is a central sectional elevation thereof.

Fig. 10 is a fragmentary detail in elevation of the pawl and ratchet device of the 65 feeding mechanism as seen from the right of Fig. 5.

Fig. 11 is a detail view in outside elevation of the operating crank.

Fig. 12 is a fragmentary detail in section 70 of the end of the ink roll spindle showing the roll retaining means in inoperative position.

Fig. 13 is a section of the same part in elevation showing the retaining means in 75 operative position.

Fig. 14 is a horizontal section showing the means for retracting the ink roll.

Fig. 15 is an elevation in section of the platen lever head and the platen. 80

In the present embodiment of the invention the operating parts of the machine are supported and inclosed by a casing comprising a lower base portion 21 and an upper box-shaped frame portion 22 supported upon the base 21 and attached thereto by screws 23. These portions of the casing (see Fig. 3) are partially separated by a horizontal slot 24 extending across the casing through its sides and opening at the front of the machine for receiving the paper to be printed, and a plate 25 on the base 21 of the casing forms the lower side of the slot and serves as a supporting bed for the paper in its passage 95 through the slot.

There is provided in the upper portion 22 of the casing above the slot a type drum or cylinder 26 fixed to a shaft 27 which is rotatably journaled at its ends in bearings 100 28 and 29 in the sides of the casing. The type wheel carries fixed upon its periphery a plurality of type forms 30 arranged parallel with the axis of the shaft 27, and the type wheel is so positioned in the casing 105 that these type forms when brought into printing position at the bottom of the wheel will lie just even with the top of the

slot 24. It will also be noted by reference to Fig. 4 that the type forms are arranged upon the wheel with their rear ends in alignment circumferentially of the cylinder 5 for a purpose which will presently appear. A guard plate 163 attached at its ends to the casing extends across the slot under the type wheel and is provided with an elongated opening above the platen so that the 10 paper is protected from contact with the type wheel except when pressed through the opening by the platen against the type form at the printing point.

The shaft 27 has fixed at its left end 15 adjacent to the casing a gear wheel 31 with which meshes a gear wheel 32 fixed upon a stub-shaft 33 rotatably journaled in the left side of the casing and projecting on the outside of the latter for the attachment 20 of a hand wheel or knob 34. By means of this knob 34 the type wheel may be rotated to bring any desired type form into printing position over the slot 24. It will be noted that the gear 32 has a greater number 25 of teeth than the gear 31, so that only a partial rotation of the knob 34 is necessary to produce a complete rotation of the type wheel. This feature allows the type wheel to be completely rotated by turning the 30 knob 34 through a conveniently small distance, and together with the ample knurled surface of the knob affords a very convenient means for positioning any selected type form in printing position.

35 An important feature of machines of this type is the provision of a readily legible dial and pointer for indicating the rotary position of the type wheel. It has been a common practice to place the dial upon the 40 periphery of a wheel or disk fixed to the shaft of the type wheel, but the disadvantage of this arrangement is that it is impossible to see at one time more than a minor portion of the whole range of characters on the dial and, furthermore, the rapid selection of any 45 desired character on the dial is made difficult by the rotational movement of the dial itself. We have conceived a convenient arrangement for obviating these difficulties, 50 which will now be described.

The casing is provided with a substantially plane top formed by plate 35 removably attached to the casing by means of screws, shown in Figs. 1 and 4, to provide for ready 55 access to the interior parts. This plate 35 is inclined downwardly toward the front of the machine so that its surface is readily visible to the operator, and the central portion of the plate is provided with a swell or flange 60 36, in which is seated a dial 38 visible through a corresponding opening 37 in the plate. The dial extends from front to back of the machine and carries thereon, arranged substantially in a column, the various printing characters corresponding to the type 65

forms upon the type wheel. A movable pointer 39 projecting between the casing and the dial at its left side into proximity to the printing characters (see Figs. 4 and 5) is supported upon a carriage 40 adapted to 70 move up and down a guide rail 44 extending parallel with the dial.

The carriage 40, referring to Figs. 7, 8 and 9, is provided with horizontally extending arms 41 and a vertically extending plate 75 42, each carrying grooved rollers 43 adapted to embrace and roll along the edges of the angular guide rail 44. The carriage 40 and its attached pointer 39 are moved up and down the guide rail 44 by means of a band 80 or cord 45 passing over guide lugs 46 on the plate 42 and through a bore 47 in a small block 48 adapted to be adjusted up and down on the plate 42 between guide lugs 49 on said plate. The block 48 has shallow channels in 85 its ends in which the band is snugly seated between the block and the guide lugs 49 and the band is thus frictionally secured to the carriage 40. The block 48 is adjusted by means of a screw 50 which passes through a 90 threaded opening therein and is rotatably supported at its lower end by lugs 51 on the plate 42 engaging a groove 52 in the lower end of the screw. The above described means for attaching the cord 45 to the carriage 40 95 serves as a tension adjusting device for regulating the tension of the band. It will be seen that by turning the screw 50 by means of a slot in its upper end, the block 48 will be made to travel up and down between its 100 guiding lugs, thus drawing a smaller or larger portion of the band into the convolution and thereby varying the tension in the band.

The band 45 extends parallel with the 105 guide rail 44 and passes over guide pulleys 53 and 54 at the ends of said rail and thence downwardly in crossed relation about a grooved pulley 55 fixed to the left end of the type wheel. The band is given one or more 110 turns about the pulley 55 to insure a proper amount of friction, and may also be pinned to the surface of the pulley to positively insure against any slip of the band on the pulley surface. The casing opposite the gear 32 is provided with a lug 56 in position to be struck by pin 57 on said gear for preventing over travel of the band 45. Instead of the band or cord 45, a sprocket chain or other 115 equivalent connection might of course be employed.

The operation of this indicating device is suggested by the description of its construction. As the type wheel is revolved by means of knob 34, the band 45 is driven by 120 the pulley 55 on the type wheel and by means of its attachment to the carriage 40 shifts the pointer 39 up and down the column of characters on the dial 38. Thus the whole 125 range of characters provided on the type 130

wheel is constantly visible on the stationary dial 38, and the pointer 39 may be quickly and conveniently positioned opposite any character on the dial by means of the knob 5 34, thus bringing the corresponding form on the type wheel into printing position.

The paper to be printed, having been placed in the slot 24 of the casing, is pressed against the characters on the type wheel by 10 means of a platen 58 adapted to be moved upwardly through a slot 59 directly below the type wheel in the plate 25 of the base portion of the casing. The platen is an elongated metal bar extending parallel with the 15 type forms and having an impression surface common to all the type forms for individual coöperation therewith and adapted to be raised squarely against the same. The platen and type forms are provided with co- 20 operating surfaces adapted to disrupt the fiber of the paper simultaneously with the printing operation, so that the paper is thoroughly impregnated with ink, such for instance, as the construction disclosed in Letters 25 Patent of the United States, No. 793249, granted to Libanus M. Todd, June 27, 1905, for "printing apparatus." However, as the construction of these members forms no part of the present invention, a detailed description 30 thereof is deemed unnecessary. The platen is supported in a slot in the head 60 at the forward end of one arm 61 of a bell-crank lever 62 having an arm 63, extending upwardly into the top of the casing. This 35 lever is pivotally supported by means of a bearing 64 on a shaft 65 supported at its ends in the sides of the upper portion 22 of the casing. The platen is adjustable in the head 60 by means of thrust screws 150 and a re- 40 tracting screw 151, shown in Fig. 15.

The platen lever 62 is actuated by means of a cam 67 fixed upon the main operating shaft 69 which extends across the casing, and is rotatably journaled in the sides thereof, 45 the right end of the shaft projecting outside of the casing and carrying an operating crank 130 which will be described hereafter. The cam 67 is provided with a high portion 68 which is adapted during the latter portion 50 of each rotation of the shaft to contact with a surface upon the upwardly extending arm 63 of the platen lever and to rock the lever, raising the platen at the forward end of the lever and forcing it with considerable 55 pressure against the type form above. This construction affords an effective leverage for producing the pressure necessary to disrupt the paper and press the ink through it. The platen is normally retained in a lower or in- 60 operative position by means of a spring 77, later to be described, which engages in an eye in the lug 70 upon the upwardly extending arm 63 of the platen lever.

It has been a common practice in machines 65 of this same general type to support the type

wheel and platen operating member in the upper portion of the casing above the slot, and the platen in the lower portion of the casing below the slot. This construction brings the operating stresses upon the casing at its weakest section, that is, at the plane of the work slot, and as a result the type wheel and platen are not rigidly supported relatively to each other and the casing is frequently broken at this point. This 70 is especially true where, for convenience in manufacturing as well as in assembling the machine, the upper and lower portions of the casing are formed as separate castings and bolted together. In the construction 75 which we have devised, however, the type wheel, platen operating shaft and platen are all supported in the upper integral frame of the casing. This arrangement therefore affords the maximum strength, as well as 80 allowing of the greatest accuracy in the assembling of the parts mentioned.

The means for inking the type wheel consists of a large inking roll 71 journaled upon a spindle 72, one end of which is fixed in an 85 arm 73 extending downwardly from a sleeve 74 rotatably carried by a spindle 75 supported in the sides of the casing. The inking roll is removably held on the spindle 72 by a means which will be presently described, and 90 an opening is provided in the adjacent side of the casing to permit the withdrawal of the ink roll for cleaning and reinking the same. This opening is shown at 66 in Fig. 3, and means is provided for retracting the 95 inking roll from the type wheel and centering it opposite the opening 66 so that it may be removed, comprising a push button 160 (Fig. 14) in the side of the casing having a 100 conical head 161 adapted to be moved into 105 contact with a similar head 162 on the arm 73, so that while the push button is normally pressed outwardly it may be pushed in to swing arm 73 to one side and bring the roll 71 opposite opening 66 in the casing. The 110 sleeve 74 is provided with an upwardly extending lug 76 to which is attached one end of the spring 77, the other end of which has already been described as attached to the upper arm of the platen lever. The spring 115 77 thus serves the double function of holding the upper arm of the platen lever against its cam with the platen in retracted position, and also of pressing the inking roller into 120 rolling contact with the type wheel. The roll is so located that as it drops in between adjacent type forms on the wheel in the rotation of the latter, it serves to approximately center one of the type forms directly 125 above the platen.

The device for retaining the ink roll upon its spindle comprises a spring bail 126, (Figs. 12 and 13) having its ends turned inwardly to engage in a bore 127 in the spindle 72 adjacent the end of the ink roll. 130

The end of the spindle is provided with diametrically placed longitudinal recesses 128, and also with a pair of diametrically placed recesses 129 perpendicular to recesses 128 and to the opening 127. Thus, when the bail 126 is turned to extend longitudinally of the spindle its sides spring into the recesses 128 and the ink roll may be freely removed from the spindle. When, however, the bail 126 is turned at right angles to the spindle its sides engage in the shallow recesses 129, retaining the bail in this right-angular position. The bail thus serves to hold the inking roll upon the spindle and any pressure that the roll exerts is applied at or so near the pivotal axis of the bail that the position of the latter can not be disturbed. This provides a very simple and effective means for retaining the ink roll in place.

20 A more precise means than the ink roll as described above for centering the type forms in printing position comprises a disk 78 attached to the left end of the type wheel and having on its periphery a plurality of notches 79 provided with beveled sides and positioned to correspond with the various type forms. Coöoperating with this notched disk 78 is a pivoted arm 80, carrying at its forward end a pointed dog 81 adapted to enter and snugly fit the notches on the disk. The arm 80 is carried by a plate 82 pivotally mounted on a spindle 83 supported by the casing. The plate 82 is normally held with its arm 80 raised against the guide rail 44 above it, out of contact with the disk 78, by means of a spring 84 attached to a lug at the bottom of the plate 82. This plate carries at its upper end a lug 85 adapted to coöperate with a cam 86 carried by the main operating shaft 69. In the initial position of the shaft 69 the lug 85 is opposite a recess in the cam 86 which allows it to occupy the raised inoperative position described above, but at the commencement of the rotation of shaft 69, the high portion of the cam 86 comes into contact with lug 85 and moves the arm 80 downwardly so that its end 81, entering one of the notches of the disk 78, serves to accurately center and lock the type wheel with one of its type forms in exact printing position. The type wheel is held locked by this means until the operating shaft is rotated approximately back to its starting position.

55 The operation of printing a value upon a check requires the use of two or more of the forms of the type wheel in succession, and it is therefore necessary to provide means for giving the check a feeding movement corresponding to each impression. To this end there is provided a pair of rotary feed wheels 87 having finely knurled peripheries for engaging the paper projecting through openings 88 in the bed plate 25 below the

printing slot. These feed wheels are fixed upon a shaft 89, journaled at its forward end in a lug 90 supported by the bed plate 25, and its other end in the rear wall of the casing. This shaft is actuated through a pawl and ratchet mechanism hereinafter described, by a cam 91 on the main operating shaft 69. This cam contacts with an arm 92 rotatably carried by a spindle 93 supported in the side walls of the casing. Rotatably carried by the same spindle 93 is a lever 75 having a forwardly projecting arm 123 and a rearwardly projecting arm 94. The arm 94 has at its end a lug 95 to which is attached one end of a spring 96, the other end of which is attached to the arm 92. 80 The arm 94 is provided with a stop 97 against which strikes a lug 98 on the arm 92, as most clearly shown in Fig. 5. The spring 96 serves to maintain the arm 92 with its lug against the stop on the arm 94 so that relative movement of these arms in this direction is prevented, but the arm 92 is free to move in the other direction relative to the arm 94 against the tension of the spring 96. Pivoted upon a pin 99 at the 90 end of arm 94 is a link 100 pivotally attached at its other end to a bar 101 enlarged at its lower end (Figs. 4 and 10) in which is formed an elongated opening 102 embracing the end of the shaft 89. The bar 95 101 also has at its lower end a lug 103 to which is pivotally attached a link 104 pivotally attached in turn to a lug on a yoke 105 rotatably supported on the shaft 89. The yoke 105 carries a lug 106 upon which is pivotally mounted a pawl 107 urged by spring 108 into contact with a ratchet wheel 109 fixed on the shaft 89. For maintaining the upper end of the arm 92 against its cam on the operating shaft and the bar 101 in its lower starting position there is provided a spring 110 having one end attached at 111 to the hub of the arm 92 and its other end to a lug 112 on the rear wall of the casing. 100

It will now be understood from the construction described above that at each rotation of the shaft 69, cam 91 contacts with arm 92 which, by means of the tension of spring 96 raises the arm 94 and bar 101, thus turning yoke 105 carrying the pawl which engages and positively turns the shaft 89 by means of the ratchet wheel 109. A spring retaining pawl 145 fixed to the casing bears upon the ratchet wheel 109 to prevent backward motion of the latter during the setting movement of the pawl 107.

For holding a paper in adjusted position in the printing slot and in contact with the feed wheels we provide a clamping device comprising a pair of small presser rolls 113 journaled on an arm 114 adapted to press the paper against the top of the feed wheels 87. (See Figs. 3, 4 and 5). The arm 114 is 115 120 125

pivotedly carried by a spindle 115 supported in the walls of the casing, and has a tail piece 116 to the rear end of which is attached the lower end of spring 84, previously described as having its upper end attached to the centering plate 82. This spring therefore serves a double function of holding the centering device in inoperative position and also of urging the presser rolls 113 against the feed wheels 87. For raising the presser rolls to allow the insertion or removal of the paper there is provided a rod 118 pivotally attached at 119 to the tail piece 116 of the lever 114. Rod 118 extends vertically through an opening in the top plate of the casing and carries at its upper end a finger piece 120, by means of which it may be conveniently depressed against the tension of spring 84 to raise the presser rolls 113.

In order to simplify the operation of the machine we have provided an automatic means so that when the presser rolls are raised to withdraw the paper upon completion of one printing operation they will be retained in raised position and automatically released to clamp the paper at the commencement of a subsequent printing operation. This means comprises a catch 121 in the form of a recess in the rod 118 and a coacting lug 122 on the plate 82 of the centering device. (Fig. 3). The spring 84 normally holds lug 122 in contact with the rod 118 so that when the latter is depressed the catch 121 engages under the lug 122 and so holds the presser rolls in elevated position. At the beginning of the next printing operation, however, as previously pointed out, the cam 86 contacting with lug 85 on the plate 82 actuates the centering dog and at the same time carries the lug 122 out of contact with catch 121 and so immediately releases the presser rolls which descend and clamp the paper in position.

It will be understood from the foregoing description that a means is provided for positively feeding the paper forward for each printing impression, but since the characters on the type wheel are of different lengths as, for example the words "One" and "Seventeen", it is necessary to provide a device for controlling the amount of the feeding movement given to the paper to correspond with the length of the printing character to be impressed. This device comprises a disk 125 (Fig. 5) fixed to the shaft of the type wheel at its right end adjacent to the casing and having its periphery cut to form a series of stop shoulders corresponding to the various type forms on the type wheel, each of which stop shoulders is located at a radial distance from the center of shaft 27 determined by the relative length of its corresponding form on the type wheel.

Coöperating with these stop shoulders the lever arm 123 mentioned above is provided with a projecting end 124 adapted to contact with the stop shoulder corresponding to the type form placed at the printing position. Since the arm 123 is a part of the same rigid lever as arm 94 which actuates the feeding device, it will be apparent that the amount of feeding action imparted to the latter is determined by the particular stop shoulder which is placed under the end 124 of lever 123 and that when lever 123 is prevented from descending farther by one of the stop shoulders, the arm 92 actuated by cam 91 will turn idly about its pivot, stretching the spring 96 without further actuating the feeding device. There is thus provided a yielding connection between arm 92 and the feeding mechanism so that while the arm 92 is given a constant throw at every revolution of the operating shaft, the amount of feeding action imparted to the feed wheels is determined by the gage member 125 to correspond with the length of the character to be printed.

Referring to Figs. 3 and 5, it will be seen from the relative angular arrangement of the several actuating cams on the operating shaft 69 that as the latter is rotated from initial position the first effect is that the type wheel is immediately centered and locked with the selected type form in precise position for coöperation with the platen. Next, the feeding mechanism is actuated to advance the paper so that the printed impression made upon the paper during the previous operation of the machine is moved along and there is brought into printing position under the type wheel a blank portion of paper just sufficient in length to receive the new impression properly spaced from the previous impression. The platen is then actuated to press the paper against the type wheel and produce the printed impression, and finally, the centering device is returned to inoperative position, releasing the type wheel for adjustment for the next operation.

The actuation of the feeding devices before, rather than subsequently to, the actuation of the printing couple during each printing operation, together with the use of an operating member manually actuated through a complete rotation has a definite purpose in our machine the advantage of which will now be described. It has been a common practice in machines of this type to employ a reciprocating operating handle manually actuated through the first half of its stroke, during which the impression of the printing couple is made and a spring placed under stress which then acts to return the operating handle to starting position.

tion and at the same time to actuate the feeding mechanism. After the handle has been moved through the first half of its stroke its return may be retarded by the hand so that it moves gently back to starting position, or the handle may then be entirely released so that it is thrown sharply back to initial position by the full force of the spring. In the first case the paper is given a minimum amount of feed, whereas in the second case the inertia of the feeding mechanism results in excessive feeding and a wide space between the impressions. Furthermore, the spacing between impressions will be varied with any variation in the strength of the spring, and as it is one of the essential requisites to the protection afforded by a check writing machine to avoid undue spacing of the words, this type of construction has proven objectionable.

In the present invention the machine is actuated by a complete revolution of the operating crank by hand, without resort to spring pressure except for returning parts to their initial positions, and it has been found that in practice the crank will be rotated at quite uniform speed by the operator. The actuation of the feeding mechanism occurs during the beginning of the rotation of the crank, when its motion is most uniform and the printing couple is actuated during the latter part of the rotation of the crank when the momentum is greatest. This arrangement obviates the difficulties pointed out above.

The object of the arrangement of the type forms with their rear ends in alignment circumferentially of the wheel will now be understood. Since the feeding movement occurs previously to the impression during each printing operation, and its amplitude is determined by the length of the impression about to be made and without reference to the length of the previous impression, it is necessary that the rear end of the previous impression should be always located in the same position relatively to the type wheel and that the rear end of the impression about to be made should come to the same position as its type form is rotated to the printing point, so that the length of the impression about to be made may be measured off between these two rear ends by the feeding mechanism. The rear ends of all the type forms therefore occupy a common position relatively to the type wheel in a line extending circumferentially thereof.

A work gage for assisting in the proper location of the work in the slot is provided on the base portion of the casing, (Fig. 2) and comprises a sliding clip 138 having its forward end 139 extending upwardly across the work slot for determining the distance

to which the work is to be inserted in the slot. The clip is guided for adjustment back and forth by means of a slot 140 in the clip and a clamping screw 141, and also by a small lug (not shown) on the inside of the forward end 139 engaging in the work slot. The clip is provided with a pointer 143 moving over a scale 144 for convenience in adjustment.

The operation of printing a check will now be briefly described. The finger piece 120 having been depressed to raise the presser rolls, the check is placed in proper position in the work slot and the knob 34 is then turned to select the first character to be printed, which is usually the line of stars shown on the dial and serving as a limiting or stopping off character. The crank 131 is then given a complete rotation. This centers the type wheel, allows the presser rolls to bear upon the paper, feeds the paper forward to receive the impression, produces the impression and then retracts the centering device. The knob 34 is then turned to select the next character. If the amount to be printed is say, \$375.41, the pointer is brought in succession opposite the characters "3", "Hundred", "70", "5", "Dollars", "40", "1", and finally "Cents," and each setting of the pointer on the dial is followed by a stroke of the crank 130 to feed and print the paper. The operation completed, the finger piece 120 is then depressed to raise the presser rolls and release the check which may then be withdrawn.

The main operating shaft 69 extending through the right wall of the casing is provided with a removable operating crank 130 having a handle 131, as shown in Figs. 4, 6 and 11. Referring to Figs. 6 and 11 it will be seen that the end of the crank 130 is formed with a V-shaped opening the inclined sides of which are adapted to slide into correspondingly inclined grooves 133 adjacent the end of shaft 69. By this means the crank is securely fixed to the shaft for rotating the latter and it will be noted that the crank can only be placed on the shaft from one side so that it is always assembled in proper relation. The crank 130 has attached thereto a spring plate 134. The lower end of this plate as seen in Fig. 11, is rigidly attached to the crank by means of a pin 135 and its upper end is guided by a pin 136 so that this end can be sprung away from the crank. This end of the plate has a circular opening 132 adapted to spring over the circular end of the shaft 69 outside of the grooves as the crank is slid into place, so that the crank is thus securely attached to the shaft 69 and, at the same time, by manually springing the plate off the end of the shaft the crank may be readily removed for the purpose of preventing

unauthorized operation of the machine and for convenience in packing.

The security against alteration of the printed impression of value on a check requires that there be no excessive spacing between the words to allow of the insertion of letters or words to change the value expressed. In the usual machine of this type an inadvertent and incomplete movement of the operating member causes a feeding of the paper without a corresponding impression so that an extra space precedes the next impression. We contemplate the use of a construction to prevent the making of a faulty impression of this kind, comprising a ratchet wheel 165 (Figs. 3 and 6) on the shaft 69 and a coöperating spring pressed pawl 166 carried on the casing for insuring the completion of each stroke of the operating crank 131.

Having thus described our invention, what we claim is:—

1. A check writer comprising a casing having a substantially horizontal work receiving slot, a type carrier above the slot movable to bring a plurality of type forms, selectively, to a common printing position, a platen below the slot having an impression surface common to said type forms, a type centering device, mechanism for feeding the work through the slot, and a single rotary operating shaft rotatable in but one direction through a complete revolution, and provided with means coöperating with the centering device for actuating the latter, with separate means coöperating with the feeding mechanism for actuating it, and also with means coöperating with the platen for actuating it to produce an impression.

40 2. A check writer comprising a casing having a substantially horizontal work receiving slot, a type carrier above the slot movable to bring a plurality of type forms, selectively, to a common printing position, a platen below the slot having an impression surface common to said type forms, a type centering device, mechanism for feeding the work through the slot, and a single rotary operating shaft rotatable in but one direction through a complete rotation and having

50 fixed thereon a cam for actuating the feeding mechanism, and also a cam for actuating the platen.

3. A check writer comprising a casing having a substantially horizontal work receiving slot, a type carrier above the slot movable to bring a plurality of type forms, selectively, to a common printing position, a platen below the slot having an impression surface common to said type forms, a type centering device, mechanism for feeding the work through the slot, and a single rotary operating shaft rotatable in but one direction through a complete rotation and having

fixed thereon a cam for actuating the centering device, and also a cam for actuating the platen.

4. A check writer comprising a casing having a substantially horizontal work receiving slot, a type carrier above the slot movable to bring a plurality of type forms, selectively, to a common printing position, a platen below the slot having an impression surface common to said type forms, a type centering device, mechanism for feeding the work through the slot, and a single rotary operating shaft provided with a cam for actuating the centering device, with a separate cam for actuating the feeding mechanism and with a separate cam for moving the platen into printing contact with the type forms.

5. A check writer comprising a casing having a work receiving slot opening at the sides and the front thereof, a rotary type wheel above the slot carrying a plurality of individual type forms, a platen common to said type forms below the slot, means for rotating the type wheel, means for feeding the work through the slot, and a common operating member movable in one direction through a complete revolution to actuate the feeding means and to effect a relative printing movement between the type wheel and platen.

6. A check writer comprising an adjustable type carrier having a plurality of separate type forms, a platen common to said type forms, an operating member for actuating the type carrier and platen relatively into contact to produce the printing impression, feeding mechanism comprising a work engaging member, a spring actuated presser member adapted to bear upon the work engaging member for clamping the work therebetween, means for moving said presser member away from said work engaging member, means for holding said presser member retracted, and means automatically actuated by said operating member for releasing said presser member for engagement with the work at the commencement of the printing operation.

7. A check writer comprising an adjustable type carrier having a plurality of separate type forms, a platen common to said type forms, an operating member for actuating the type carrier and platen relatively into contact to produce the printing impression, work feeding mechanism comprising a rotary feed wheel, a spring actuated presser roll normally bearing upon the feed wheel for engaging the work therebetween, means for moving said presser roll away from said feed wheel, means for holding said presser roll retracted, and means automatically actuated by said operating member for releasing said presser roll for engagement with the

work at the commencement of the printing operation.

8. A check writer comprising a casing, a type carrier therein, a platen, an operating member for effecting a relative printing movement between said type carrier and platen, feeding mechanism comprising a work engaging member, a presser member normally bearing upon the work engaging member for clamping the work therebetween, a rod supported in said casing connected to said presser member to raise the latter, and provided with a catch, a latch plate having a lug adapted to engage said catch when the rod is moved to raise the presser member, a spring for moving the presser member into engagement with the work and for holding the latch plate in operative relation to said rod, and means on said operating member for tripping the latch plate and releasing the rod and presser member at the commencement of the printing operation.
9. A check writer comprising a casing, a type carrier, a platen, an operating member for effecting a relative printing movement between the type carrier and platen, feeding mechanism comprising a rotary feed wheel, a presser roll normally engaging the feed wheel and clamping the work therebetween, a rod supported in said casing connected to said presser roll to raise the latter and having a catch, a latch plate having a lug adapted to engage said catch when the rod is moved to raise the presser roll, a spring for moving the presser roll into engagement with the work and for holding the latch plate in operative relation to the rod, and means on said operating member for tripping the latch plate and releasing the rod and presser roll at the commencement of the printing operation.

10. In a device of the class described, the combination with a type wheel, a platen, means for centering the type wheel relatively to the platen, and a work feeding member, of a spring actuated presser member for holding the work against the feeding member, means for moving said presser member to inoperative position, a member connected to said centering means for retaining said presser member in retracted position and means for actuating said centering means to release said presser member and to center the type wheel.

11. In a device of the class described, the combination with a type wheel, a notched centering disk therefor, a platen, and a work feeding member, of a presser member for holding the work against the feeding member, means for moving said presser member to inoperative position provided with a catch, a device having a lug for co-operation with said catch to hold the presser member retracted and having also an arm

for co-operation with the notches of the said disk for centering the type wheel, a spring for actuating the presser member toward the work and for normally holding said device with its lug in operative position relative to said catch and with its arm out of contact with the centering disk, and means for moving said device for releasing the presser member and centering the type wheel.

12. A check writer comprising a casing having an upper integral frame portion, a lower base portion, and a work supporting slot between the upper and lower portions thereof, a type carrier supported in the upper portion of the casing above said slot, a member supported wholly by the upper integral portion of the casing and extending below the slot, a platen carried by said member below the slot, and operating means also supported wholly by the upper integral portion of the casing for effecting a relative printing movement between the type carrier and platen whereby the operating stresses of the machine are wholly borne by the integral frame portion of the casing above the slot.

13. A check writer comprising a casing having an integral upper portion, a base portion and a slot between said portions, a type carrier above the slot mounted in the upper portion of the casing, a bell-crank lever supported wholly by the upper integral portion of the casing and having one arm extending below the slot, a platen carried by said arm below the slot, an operating means supported wholly by the upper integral portion of the casing and connected with the other arm of the platen lever for effecting a relative printing movement between the type carrier and platen, whereby the operating stresses of the machine are wholly borne by the integral portion of the casing above the slot.

14. A check writer comprising a casing, a type wheel therein, a member pivotally mounted in said casing, an ink roll journaled on said member for rolling contact with the type wheel, a lever pivotally mounted in the casing, a platen carried by said lever for co-operation with the type wheel, a spring connected to said member to press the ink roll against the type wheel and to said lever to maintain the platen normally in inactive position, and means for actuating the platen into printing contact with the type wheel.

15. In a check writer having a work receiving slot; a type carrier; a platen; a platen operating lever, said lever and the type carrier both having their supports on the same side of the work receiving slot and the lever being shaped to hold the platen at the other side of the slot to per-

mit insertion of the work between the type and platen, and means for effecting relative movement of the type and platen whereby to print.

5 16. In a check writer having a work receiving slot; a type carrier; a platen; a platen operating lever, said lever and the type carrier both having their supports on the same side of the work receiving slot

and the lever being formed to hold the 10 platen clear of the type carrier and at the other side of the slot whereby to permit insertion of the work between the type carrier and platen, and means for operating the platen lever to cause printing engagement 15 of the platen with the type.
